UNITED STATES PATENT OFFICE.

STEPHEN PEARCE QUICK, OF JOHANNESBURG, SOUTH AFRICAN REPUBLIC.

MACHINE FOR SHAPING OR FORGING AND SHARPENING ROCK-DRILLS, &c.

SPECIFICATION forming part of Letters Patent No. 606,390, dated June 28, 1898.

Application filed August 19, 1897. Serial No. 648,800. (No model.) Patented in South African Republic December 13, 1895, No. 1,027, and September 24, 1896, No. 1,217.

To all whom it may concern:

Be it known that I, STEPHEN PEARCE QUICK, a subject of the Queen of Great Britain, residing at Johannesburg, in the South African Republic, have invented certain new and useful Improvements in Apparatus or Machines for Shaping or Forging and Sharpening Rock-Drills and the Like, (for which I have obtained Letters Patent in the South African Republic, No. 1,027, dated December 13, 1895, and No. 1,217, dated September 24, 1896,) of which the following is a specification.

This invention relates to an apparatus or machine primarily designed for shaping or forging and sharpening that class of rock or like drills commonly termed "jumpers" or "chisel-bits," which are employed for the formation of holes in rock, stone, &c., for blasting operations in gold or other mines. Although primarily and more particularly designed for this special purpose, it will be evident that the machine may be employed for the forging, shaping, and sharpening of other similarly-shaped edged tools, such as chisels and the like.

It is designed with the object of producing an efficient machine for performing the several operations requisite to produce a satisfactorily sharpened drill capable of being driven at a high speed, and at the same time one of comparatively simple and consequently cheap construction, and one which if, desired, will be within the capacity or complete control of one man.

It consists, essentially, of a machine constructed with upper and lower die-blocks, to the upper one, preferably, of which a reciprocating motion is imparted through the medium of a crank or eccentric connecting-rod and cross-head or slide working in slide-bars or guides formed on or attached to the framing of the machine or operated in any other suitable and convenient manner, in or to which die-blocks any desired and convenient number of dies for effecting the sharpening of varying sizes of drills are sunk or fitted, arranged, preferably, in two sets, one set for forging or forming the tapering, flat, or angular faces of the drill and the other set for forging or forming the drill on its slightly spreading sides or edges, the halves of the

dies for forming the tapering or flat faces of the drill sunk in each die-block being fitted with adjustable cutters so disposed or arranged within the die-blocks as to impart the desired bevel to the extremity of the drill and to form the sharp chisel-shape cutting edge thereon when the halves of the dies are brought to coincide and to shear off any superfluous metal, and also, in combination with the periphery of the fly-wheel of the machine, of an adjustable cutter working in conjunction with an adjustable normally-stationary cutter supported in an extension or projection of the framing directed toward the periphery of the fly-wheel, or in a bracket affixed thereto, for removing the bur or fine edge or strip of metal usually left on the cutting edge of the drill after it has been passed through the dies, and thereby to complete the sharpening or formation of the cutting edge on the drill.

The invention will be further and fully described by aid of the sheet of drawings hereunto annexed.

In the drawings, Figure 1 is a front elevation of the machine; Fig. 2, an end elevation of same, partly in section, and showing one of the dies for forming the tapering or angular faces of the drill, the means for adjusting the cutters constituting that part of each half of the die which imparts the required bevel to the drill and forms the extreme cutting edge thereon and also the means for adjusting the lower die-block; Fig. 3, a transverse sectional elevation of a portion of the upper and lower die-blocks, showing one of the dies sunk therein for forming the tapering or flat faces of the drill drawn to an enlarged scale; Fig. 4, plan of one-half of the die and die-block shown in Fig. 3. Fig. 4^a is a plan of the lower die-block J, drawn to a still larger scale to show the slightly-rounded and beveled cutting edge of the cutters m or m'. Fig. 4^b shows several detail views of one of cutters m; Fig. 5, a transverse sectional elevation of a portion of the die-blocks, showing one of the dies sunk therein for forming the slightly-spreading sides or edges of the drill; Fig. 6, a plan of one-half of the die and die-block shown in Fig. 5. Fig. 6^a is a similar view to Fig. 5, but drawn to an enlarged

scale to show the slightly-rounded inner end n^2 of dies M, M', or M². Fig. 7 is an end elevation of the machine, showing a drill V in position for the removal of the bur v by the 5 cutters Q and R. Fig. 7^a shows several detail views of cutter Q. Fig. 7^b shows several detail views of cutter R.

A is the preferably cast-iron frame of the machine, of any suitable construction and design, comprising a base a and two standards or pedestals a' a², in which is journaled the eccentric-shaft B, to one extremity of which is keyed or otherwise attached the driving-pulley C, speed-cone, or fast and loose pulleys, and to the other the fly-wheel D.

On the eccentric-shaft B and between its bearings the connecting rod or link E is mounted, which is connected by means of a pin F, bolt, or the like with the cross-head G, 10 working in guides or recesses formed on the inside of the standards a' a². g² are studs, pins, or the like screwed through the cross-head into the pin F to secure same thereto and to prevent its rotation therein. To the 15 front of the standards a' a² are fixed, by means of set-screws h h' or the like, the retaining-plates H' H², forming the front portion of the guides or recesses in which the cross-head G works.

20 The underside of the cross-head G is formed with a preferably dovetail recess g, in which fits a correspondingly-shaped projection or piece g', formed on the top of the upper die-block H. A wedge-shaped key h² is preferably inserted and tightly driven in at one side between the recess g and the projection g' to firmly secure same therein and to prevent the possibility of its working loose while the machine is running. The upper die-block 25 H is by this means firmly connected with the cross-head G, and the requisite reciprocating motion is thereby imparted to it on the rotation of the shaft B.

Within the center of the base a of the machine-frame, which is hollowed out to receive it, is fitted a wedge or block K, formed with an inclined upper surface k and provided with adjusting screws, studs, or bolts k' k² for effecting any desired vertical adjustment of 30 the lower die-block through the medium of the wedge K. The screws, studs, or bolts k' k² pass in from the exterior of the frame, which is tapped to receive them, and are provided with lock-nuts or other suitable devices 35 for locking same in position after any required adjustment has been effected.

J is the lower die-block, fitted within the center of the base a and resting upon the adjusting-wedge K. It is formed with an inclined under surface j, corresponding with the inclined upper surface of the wedge K.

j² j' j⁴ are studs or screw-bolts provided with lock-nuts screwed through the base of the frame and abutting the sides of the lower die-block on the inside for firmly securing same therein horizontally. Studs or screw-bolts j', passing through holes formed in the lower

die-block J and through preferably open-ended slots formed in the adjusting-wedge K and screwing into the base a of the frame on the inside, are provided for securely bolting the lower die-block in position vertically when adjusted.

The upper and lower die-blocks H J, respectively, are shown in the drawings sunk 75 with three dies L L' L² for forming the tapering or angular faces of the drill and with three corresponding dies M M' M² for forming the slightly-spreading sides or edges thereof.

The machine as thus constructed is capable of accommodating or forging and sharpening three different sizes of drills.

It will be perfectly evident that the capacity of the machine or the number of dies may be increased or decreased, as may be desired.

The form and construction of the dies L L' L² is more clearly shown in Figs. 2, 3, 4, and 4^a of the drawings. In the upper and lower die-blocks H J are sunk or fitted half of the complete die, having the form of the drill or 90 tool at its cutting extremity or so formed that when brought together they form a cavity or recess in the blocks exactly corresponding with the external shape of the tool at this part. The dies L L' L² have the surfaces corresponding to the tapering or angular faces of the drill sunk approximately horizontal or so that the drill when placed between them to be sharpened receives the full force or blow on its tapering or angular faces. The upper 100 and lower die-blocks are constructed with inclined slots l l', projecting into or terminating at the inner ends of the dies, in which are fitted preferably hardened-steel cutters m m', slightly rounded and beveled, as seen more 105 particularly in Figs. 4^a and 4^b, to form the slightly rounded and beveled cutting edges on the drill and to shear off any superfluous metal that may be fed or placed between the dies. The cutters m and m', as seen in Figs. 110 4^a and 4^b, are slightly dished out or hollowed on their face or surface m², which projects into and forms the inner end of the die, the inner end of the die being rounded or curved correspondingly, as shown in Fig. 4^a, and they 115 are beveled and slightly rounded on their cutting edge from end to end, as seen at m³, Fig. 4^b. These cutters, it will be perceived, when in position complete the form of or constitute the innermost portion of the die. The 120 slots l l' are cut or formed at any desired angle or inclination, according to the bevel required on the edge of the drill or tool. For the particular purpose for which the machine is designed it is found that the cutting of the 125 slots at an angle of about forty-five degrees is productive of satisfactory results. It will be evident that the inclination may be varied as may be desired.

For the purpose of setting or effecting any 130 required adjustment of the cutters m m' wedges or tapered bolts n n' are provided, passing through slots o o', formed in the die-blocks and intersecting the slots l l' and bear-

ing upon the inner extremities of the cutters $m m'$. The wedges $n n'$ are screwed and fitted with nuts by which they may be drawn forward to adjust the cutters. Stops or rests O are fitted by set-screws or otherwise to the upper die-block opposite each of the dies L , L' , L^2 or carried the full length of these dies.

The form of the dies M , M' , M^2 is clearly shown in Figs. 5, 6, and 6^a of the drawings. 10 These dies are similar to those shown in Figs. 2, 3, 4, and 4^a , except that they are sunk or fitted in the die-blocks at right angles thereto or so that the pressure of the upper block is received upon the slightly-spreading sides or 15 edges of the drill to complete the formation of the drill to the required size or gage.

Fig. 6^a shows the slightly-rounded inner end n^2 of the die for forming the slightly-rounded extremity of the drill.

20 On the fly-wheel side of the frame of the machine an extension or bracket P is preferably cast or formed separate and bolted or otherwise affixed thereto. This projection or bracket P is formed with a vertical slot p , 25 in which is fitted a preferably-hardened-steel cutter Q , held in position therein by means of straps or bars $q q'$, secured in position by means of set-screws or the like $q^2 q^3$. A screw bolt or stud r , passing in through the under 30 side of the bracket P and provided with a lock-nut r' , is employed for effecting the vertical adjustment of the cutter Q . In the periphery of the fly-wheel D a slot d is formed, in which is fitted a corresponding cutter R , provided 35 with holding and adjusting screw bolts or studs $r^2 r^3$. The cutters Q , R are so arranged and set that as the fly-wheel revolves the cutter R just passes over the cutter Q . The cutters Q and R are preferably slightly 40 rounded and beveled off to correspond with the curvature of the cutting edge of the drill or tool. The cutter Q (see Fig. 7^a) is precisely similar in construction to the cutters m and m' —that is to say, it is slightly dished 45 out on its front face at s and beveled and slightly rounded from end to end, forming a convex cutting edge, as seen at s' . The cutter R (see Fig. 7^b) is slightly rounded inwardly or in the opposite direction and a 50 concave beveled cutting end t thereby formed. The cutter R is rounded on the front or forward face, as shown at t' , instead of being dished out, as is the case with its corresponding cutter Q .

55 A rest or support T , as shown in dotted lines, Fig. 1, formed with notches or recesses t^2 in line with the several dies, will preferably be bolted or otherwise affixed to the frame of the machine, and a similar rest U will also be 60 provided for supporting the stock or shank of the drill V while the bur or fine strip of metal v is being removed by the cutters Q and R .

In the working of the machine after the 65 requisite adjustment of the several parts has been effected the drill to be sharpened or the metal from which the drill is to be formed

having been raised to the requisite temperature is placed between one or other of the dies L , L' , or L^2 corresponding to its size, and 70 thereby has the tapering or angular faces of the die imparted to it, the cutting edge being at the same time formed by the cutters. It is now placed in the corresponding die M , M' , or M^2 , as the case may be, and is finished on 75 its spreading edges and corners. The drill is now finally placed in the rest U in such a position as to bring the fine strip of metal or bur v left by the dies on the edge of the drill in line with or resting on or projecting over 80 the cutting edge of the lower cutter Q , and the cutter R , fixed to the periphery of the fly-wheel D , as it revolves shears off the bur v , leaving the drill V with a clean sharp cutting edge. The drill is now tempered and is then 85 ready for use.

Having fully described my invention, what I claim, and desire to secure by Letters Patent, is—

1. A die for shaping or forging and sharpening rock-drills and similarly-shaped edged tools fitted with an inclined cutter so disposed or arranged as to constitute that portion of the die which effects the formation of the extreme cutting edge on the drill simultaneously 90 with the formation of the tapering or angular faces, said cutter being set at such an inclination as to form the desired bevel at the cutting-point of the drill in addition to the cutting edge substantially as described.

2. A die for shaping or forging and sharpening rock-drills and the like in which is arranged an adjustable inclined cutter for imparting the desired bevel to the drill at the cutting-point and also to form the extreme 105 cutting edge thereon simultaneously with the formation of the tapering or angular faces substantially as described.

3. In combination, the die for forging or shaping and sharpening rock-drills and like tools, the adjustable inclined cutter, constituting a portion of the die, slightly rounded and beveled to form the slightly rounded and beveled cutting edge on the drill simultaneously with the formation of the tapering or 115 angular faces thereon substantially as described.

4. A die-block in which is sunk or fitted a die for shaping or forging and sharpening rock-drills and the like provided with an inclined slot projecting into or terminating at one end of the die in which is fitted a removable cutter constituting that portion of the die which effects the sharpening or formation of the extreme cutting edge on the drill substantially as described.

5. In combination, a die-block, a die sunk or fitted therein for shaping or forging the tapering or angular faces on rock-drills and like tools, an inclined slot formed in the die-block projecting into said die, a cutter arranged therein and forming that portion of the die which effects the sharpening or formation of the extreme cutting edge on the

drill, a further slot formed in the die-block, intersecting the inclined slot in which the cutter is arranged and an adjusting-wedge or tapered bolt fitted within this further slot and bearing against the end of the cutter for effecting any required adjustment thereof substantially as described and shown.

6. In machines or apparatus for shaping or forging and sharpening rock-drills and the like the combination of upper and lower die-blocks to the upper one of which a vertical reciprocating or up-and-down motion is imparted in any suitable manner, the die-blocks being sunk or fitted with one or more dies for effecting the shaping and sharpening of drills or tools on their tapering or angular faces, said die or dies being fitted or provided with an adjustable cutter or cutters for forming the extreme cutting edge on the drill simultaneously with the formation of the angular faces and with one or more dies for forming the drill on its slightly-spreading sides or edges and finishing same to gage substantially as described and shown.

15 7. In machines or apparatus for shaping or forging and sharpening rock-drills and the like the combination of upper and lower die-blocks to the upper one of which a vertical reciprocating or up-and-down motion is imparted in any suitable manner, the die-blocks being sunk or fitted with one or more dies having tapering and angular faces for effecting the shaping and sharpening of drills or tools on their tapering or angular faces, said die or dies being fitted or provided with an adjustable cutter or cutters slightly rounded and beveled and set at such an inclination in the blocks as to form the desired bevel at the cutting-point and the slightly rounded and beveled cutting edge of the drill simultaneously with the formation of the tapering and angular faces thereof substantially as described.

8. In machines or apparatus for shaping or forging and sharpening rock-drills and like tools, the combination of the upper and lower die-blocks H J, in which are sunk or fitted the set or series of dies L L' L² for forming the tapering or angular faces of the drill, the inclined slots or holes l l' formed in the die-blocks and terminating at the inner ends of the dies, the cutters m m' fitted within the slots l l' and constituting the innermost portion of the dies, the slots or holes o o' formed in the die-blocks and intersecting the slots l l', the wedges or tapered bolts n n' fitted in slots o o' and bearing upon the extremities of the cutters m m' for adjusting same as may be desired and a rest or stop O substantially as described and shown.

9. In machines or apparatus for shaping or forging and sharpening rock-drills and the like the combination of the bracket or extension P of the frame, the slot p formed therein, the slightly rounded and beveled cutter Q fitted within slot p, the straps or bars q q' affixed to the bracket P and securing cutter

Q in position in the slot p, the adjusting-screw r for the cutter Q, the fly-wheel D, the slot d formed in the rim or periphery thereof, the 70 slightly rounded and beveled cutter R fitted within the slot d, the retaining-stud r² and adjusting-screw r³ for the cutter R for shearing off the bur or fine edge or strip of metal left on the cutting edge of the drill or tool 75 after it has been passed through the dies substantially as described and shown.

10. In machines or apparatus for shaping or forging and sharpening rock-drills and the like the combination of the frame A of the 80 machine, comprising the base a and the standards or pedestals a' a², the shaft B journaled therein, the driving-pulley C, the fly-wheel D, the cross-head G working in guides or recesses formed on the inside of the pedestals a' a² and 85 coupled up with the driving-shaft B by means of an eccentric, crank or other suitable device to impart a vertical reciprocating or up-and-down motion thereto on the rotation of the shaft, the recess g formed in the cross-head G on the under side, the upper die-block H, the projection g' fitting and secured within the recess g, the dies L L' L² sunk or fitted within the die-block H, the inclined cutters m m' the adjusting-wedges or tapered 90 bolts n n', the stops or rests O, the dies M M' M² sunk or fitted within die-block H, the lower die-block J, the dies L L' L² sunk or fitted therein, the inclined cutters m m', the adjusting-wedges or tapered bolts n n', the dies 95 M M' M² sunk or fitted within die-block J, the tapered or inclined under surface j of the die-block J the adjusting-wedge K fitted within the base a upon which block J rests, the holding and adjusting screws or studs j² j³ j⁴ k' k² 100 for the wedge K and the holding-down bolts j' for the lower die-block J substantially as described and shown.

11. In machines or apparatus for shaping or forging and sharpening rock-drills and the 110 like, the combination of the frame A, comprising the base a and the standards or pedestals a' a², the eccentric-shaft B journaled therein, the driving-pulley C, the connecting-rod E, the cross-head G, the pin F, the screws 115 or studs g², the retaining-plates H' H² affixed to the pedestals a' a², the recess g formed in the cross-head G on the under side, the upper die-block H, the corresponding projection g' formed thereon and fitting within the recess 120 g, the wedge or tapered key h², the dies L L' L² sunk or fitted within the die-block H, the inclined cutters m m' the adjusting-wedges or tapered bolts n n', the stops or rests O, the dies M M' M² sunk or fitted within die-block 125 H, the lower die-block J, the dies L L' L² sunk or fitted therein, the inclined cutters m m', the adjusting-wedges or tapered bolts n n', the dies M M' M² sunk or fitted within die-block J, the tapered or inclined under surface 130 j of the die-block J the adjusting-wedge K fitted within the base a upon which block J rests, the holding and adjusting screws or studs j² j³ j⁴ k' k² for the wedge K and the hold-

ing-down bolts j' for the lower die-block J, the bracket or extension P of the frame A, the slot p formed therein, the cutter Q fitted within slot p , the straps or bars qq' affixed to the bracket P and securing cutter Q in position in the slot p , the adjusting-screw r for the cutter Q, the fly-wheel D, the slot d formed in the rim or periphery thereof, the cutter R fitted within the slot d , the retaining-stud r^2

and adjusting-screw r^3 for the cutter R substantially as described and shown.

In witness whereof I have hereunto set my hand in presence of two witnesses.

STEPHEN PEARCE QUICK.
